UNITED STATES PATENT OFFICE.

JOHN THOMSON, OF BROOKLYN, NEW YORK.

MECHANICAL MOVEMENT.

SPECIFICATION forming part of Letters Patent No. 427,448, dated May 6, 1890.

Application filed March 14, 1890. Serial No. 343,899. (No model.)

To all whom it may concern:

Be it known that I, JOHN THOMSON, a citizen of the United States, residing in Brooklyn, Kings county, State of New York, have 5 invented certain new and useful Improvements in Mechanical Movements, of which the following is a specification.

This invention is a mechanical movement, and it particularly relates to the means for 10 controlling the vibrating action of the beds or platens in the instance of horizontal stamping, embossing, or printing machinery, and is an improvement in and extension of the inventions for which Letters Patent of 15 the United States were granted me as follows: Nos. 331,845 and 331,846, December 8, 1885, and No. 378,343, February 21, 1888.

The chief object of this invention is to accomplish results practically uniform with 20 those already attained, but with fewer and less complication of parts and increased smoothness and durability of action.

In the drawings, Figure 1 is a combined elevation and longitudinal center section 25 showing the prior state of the art as disclosed in the patents cited; and Fig. 2 is a view similar to the first, developed on the same center lines, but showing my present improvement.

The desirable features in actions of this 30 class will be more quickly comprehended by at once briefly describing the prior construction and operation as presented in Fig. 1. In the bed 10 of the frame 11 is mounted a main shaft 12, to which is attached on opposite 35 sides the main gears or crank-wheels 13, driven by the pinion 14. Fixed in the face of each gear-wheel is the crank or wrist pin 15. On opposite rocker-seats 16 of the frame rest the rockers 17, being a part of the bridge 40 18, to which is attached in the present case a platen 19. To the seat 20 on the lower side of the bridge is secured the bridge-cam 21, and in brackets 22, secured to the strut 23 of the frame, are mounted the pin 24 and friction-roll 25 thereon, which engage the bridge-cam. Each of the trunnions 26 of the bridge 45 and crank-pin are connected by main connecting-rods, as 27. To the face of each crank-pin is attached a "dwell-cam" 28, the 50 cam or groove 29 of which, being on the inner side, is engaged by the friction roll and pin 30 31, mounted on the face of the rod, the

crank-pin "eyes" of which 32 are slotted, as at 33. If we assume rotation of the gear, as indicated by the arrow 34, it will follow that 55 the horizontal portion 35 of the bridge-cam will first cause the platen to recede from the bed in a direct line to position 36. Then as the friction-roll 25 encounters the curved section 37 the rockers will be caused to both 60 roll and slip differentially, changing the lateral motion of the platen into vibratory movement. Continuing, we find that the form of the upper section of the cam, as from the positions 38 and 39, is such as to practically effect 65 rolling contact between the rockers and their seats, and when the point 39 of the cam reaches the center of the roll the face of the platen will be in the position indicated by the dotted outline 40, or at an angle of approximately forty-five degrees from the vertical face 70 of the bed, while at the same time the crank-pins will be at 41 and the trunnions at 42. It should be particularly observed that the action so far imparted to the platen has been at the 75 maximum speed of the crank traveling in the circuit 43; but beyond this the dwell-cams will cease to be idle, and the roll, entering the curved portion 44 thereof, will now assume control and begin to decrease the motion of 80 the platen, the crank-pins traveling forward in the slots of the rods. When the position 45 of the dwell-cam is reached, the platen is at its extreme angle, as indicated by dotted outline 46, or at sixty-eight degrees from the 85 bed, and also at this time the extremity 47 of the bridge-cam intersects the bridge-cam roller and the trunnion is at 45. Between the positions 45 and 49 of the dwell-cam its form is such that the connecting-rods and platen 90 are maintained at a rest or "dwell." The continued movement of the crank simply reverses the operation just described. Therefore it is clear that from 50 to 41 or 50 to 51 the platen is swung back or forth at the full 95 speed of the crank, but between 41 to 51 it is driven at a rate of motion less than that of the crank, and, furthermore, that such change of motion and conditions in the platen are due to the intervention of the said dwell-cams. 100

It may be here stated that an extreme angle in the platen greater than sixty-five degrees to seventy degrees from the vertical is rather objectionable than favorable to rapid

feeding, while the hand should be clear of the platen when the angle is about thirty-five degrees to forty degrees; hence the more rapidly the platen can be swung to the least practicable feeding angle the greater will be the available time thereafter. So, too, it becomes more convenient to attach apparatus to the machine in which the most efficient operation will devolve upon the greatest available space between the bed and platen for the longest period of time. In other words, this is but a phrase of the common problem—space and time.

Passing to Fig. 2, the preceding-described operation of Fig. 1 refers in every particular to this illustration in so far as relates to the positions 50 to 41 and 50 to 51 of the crank, to 40 of the platen, 42 of the trunnion, and 35 38 39 of the bridge-cam; but it will be seen that the dwell-cams, their rollers and pins, and the slots of the rods are dispensed with entirely, the eyes of the rods being bored to the diameter of the crank-pins and secured by an ordinary washer, as 52. In the bridge-cam, however, beyond point 39, the form is changed from that of Fig. 1, and this alone constitutes my invention.

Now, bearing in mind the several points in the operation as they have successively been pointed out—the crank-pin at 41 or 51, the platen at 40, the point 39 of the bridge-cam coincident with the center of the roll 25—it follows that by thus simply curving the upper section of the bridge-cam inward toward the bridge, as from 39 to 53, the consequence of this will be to cause the rockers, as 17, to slip upon the rocker-seats, (as see the double arrow 54,) and hence will swing the platen at a rate of speed differential to that of the crank, the trunnions acting as an axis.

As shown in the present illustration, the development of the bridge-cam from 39 to 53 is such that the extent of this slip shall cause the platen to swing to the same extreme angle—sixty-eight degrees—as in the primary instance; but as the connecting-rods must now constantly move with the cranks the center of the trunnions will be carried farther outward, or to the position 55. This will also be the case in the instance of the platen, (as compare the lower edges thereof at 56 57.) The conditions determining the form of the cam from 39 to 53, as here shown, are that the platen shall be cumulatively brought to or from the positions 40 to 46 at a rate of speed less than

that of the cranks while they are passing between 58 to 41 or 51, and this for the rapid operation of heavy masses is the theoretically best design; but it will be evident to mechanicians that this may be modified even to the extent of maintaining the platen at a uniform angle during a portion of the movement of the crank, or to reverse the conditions described, or to obtain a dwell by this simple expedient alone.

While this design adds nothing to the expense of construction in the part itself, it nevertheless not only accomplishes the same results as in the more complicated and expensive arrangement, but of even more importance is the fact that thereby both the smoothness, speed, and durability of the action are greatly enhanced.

What I claim is—

1. A bridge-cam having upper and lower lateral extensions, in combination with the rocker and rocker-seats and friction-roll suitably mounted, the form and construction of the upper extension of the cam being such as to cause the rockers to slip upon their seats at a rate of speed differential to that of the crank, substantially as described.

2. The combination, with the frame having a frictional roll, of a bridge-cam having a curved portion and two end portions extending in opposite directions, substantially as described.

3. The combination, with the rocker-seats and bridge rocking thereon, of a friction-roll suitably mounted and engaging a bridge-cam, the said cam having a curved intermediate portion from which extends another curved portion of shorter radius than the intermediate portion and a straight portion, substantially as described.

4. The combination, with the rocker-seats and bridge rocking thereon, of the crank-pin and connecting-rod between the crank-pin and bridge, and a friction-roll suitably mounted and engaging a bridge-cam, said cam having an intermediate portion and two end portions extending in opposite directions, substantially as described.

In testimony whereof I have signed my name to this specification in the presence of two subscribing witnesses.

JOHN THOMSON.
